The ornamental design for seat with lower cut-out, as shown and described.

DESCRIPTION

FIG. 1 is a front perspective view of the seat with lower cut-out;

FIG. 2 is a more detailed view of a portion of the cut-out of FIG. 1

FIG. 3 is a rear perspective view thereof;

FIG. 4 is a more detailed view of a portion of the cut-out of FIG. 3;

FIG. 5 is a front view thereof;

FIG. 6 is a back view thereof;

FIG. 7 is a left side view thereof;

FIG. 8 is a right side view thereof;

FIG. 9 is a top view thereof; and,

FIG. 10 is a bottom view thereof.

The dashed lines shown on the seat and backrest in all views are understood to represent stitching.
